(57) **CLAIM**

The ornamental design for a pickup cover for string instruments and electric guitars, as shown and described.

DESCRIPTION

FIG. 1 is a perspective view of the front, right, and bottom side of a pickup cover for string instruments showing an embodiment of the new design.

FIG. 2 is a front view thereof.

FIG. 3 is a back view thereof.

FIG. 4 is a right view thereof.

FIG. 5 is a left view thereof.

FIG. 6 is a top view thereof.

FIG. 7 is a bottom view thereof.

FIG. 8 is a perspective view of the front, right, and top side of a pickup cover for string instruments showing another embodiment of the new design.

FIG. 9 is a front view thereof.

FIG. 10 is a back view thereof.

FIG. 11 is a left view thereof.

FIG. 12 is a right view thereof.

FIG. 13 is a top view thereof; and,

FIG. 14 is a bottom view thereof.

The broken lines depict portions of the pickup covers for string instruments and electric guitars in which the design is embodied that are not considered part of the claimed design.

1 Claim, 8 Drawing Sheets
